UNITED STATES PATENT OFFICE.

JOSEPH C. BUECHLER, OF HAGUE, NORTH DAKOTA.

CHECK-BOOK CLAMP.

Application filed November 26, 1926. Serial No. 150,884.

My invention relates to book binding, and more especially to leaf holders; and the object of the same is to produce a device for holding back the used stubs in a check book 5 when writing new checks or posting the old stubs.

With the above and other objects in view, my invention consists in the combination and arrangement of parts hereinafter described and claimed, it being understood that, within the scope of what is claimed, changes may be made in the precise embodiment shown without departing from the spirit of the invention.

15 In the drawings:

Figure 1 is a perspective view of a check book held open by my invention.

Figure 2 is a side view of Figure 1.

Figure 3 is a plan view of my invention.

20 Referring now more particularly to the drawings, my invention comprises a single strand of resilient wire indicated generally by the reference character 1, the said strand being bent medially its ends as at 2 so as to 25 have the intermediate portions 3 extending in a common plane in spaced parallel relation; each of the terminal portions of the strand being bent in the form of a clamping loop 4, each loop being in a plane at right 30 angles to the common plane of the intermediate portions as shown at 4; the end of each loop being flared outwardly from its corresponding intermediate portion, as 3, so as to fall laterally outside of the same, as clearly 35 shown in Figure 3, and normally converging towards the common plane of the intermediate portions, the said ends being also curved 40 outwardly from said common plane as at 5 so as to facilitate the entrance of the check

stubs 6 into the said loops 4, whereby the 40 said check stubs 6 are firmly held between the ends of the loops and the spaced wires 3. The said medial portion of the wire is also bent in a direction at right angles to the common plane of the intermediate portions 3 so as to form a thumb hold 7.

45 In the use of my invention, the device is positioned over the used check stubs of a check stub as shown in Figures 1 and 2, with the thumb hold 7 outwardly the said 50 stubs, as more clearly shown in Figure 2, whereby the thumb of the person using the device may act to hold the said stubs back out of the way by pressing on the said thumb hold 7.

I claim:

A device of the kind described comprising a single strand of resilient wire bent medially its ends so as to have its intermediate portions extending in a common plane in spaced and parallel relation, the medial portion of the strand being bent at right angles to the common plane of the intermediate portions, each of the terminal portions of the strand being bent in the 60 form of a clamping loop, each loop being in a plane at right angles to the common plane of the intermediate portions and normally closing upon the said common plane, the end of each loop being flared outwardly from its 65 corresponding intermediate portion so as to fall laterally outside of the same, and being also curved outwardly from the said common plane so as to facilitate the entrance of used 70 check stubs into the said clamping loops.

75 In testimony whereof I affix my signature.

JOSEPH C. BUECHLER.
